ROTOR FOR AXIAL FLOW ELASTIC FLUID
COMPRESSORS OR TURBINESFrans Eric Ossian Östmar, Finspong, Sweden,
assignor to Svenska Turbinfabriks Aktiebolaget
Ljungström, Finspong, Sweden, a Swedish
joint-stock companyApplication July 13, 1949, Serial No. 104,561
In Sweden September 22, 1948

1 Claim. (Cl. 230—122)

1

The present invention relates to axial flow elastic fluid machines, as compressors and turbines of the rotary type and more particularly to the rotors of such machine.

The object of the invention is to provide a rotor of such a small weight and of such a great strength as to be fit for use in connection with turbines and compressors of jet propulsion units for aeroplanes.

The rotor according to the invention is built up of axial sections comprising discs having two or more axially extending cylindrical or substantially cylindrical flanges on one side or on each side, said discs being held together axially so as to form a unit by means of a central bolt, by means of which the discs are jammed together with a sufficient power to cause the abutting flanges of the discs to act as a unitary tubular shaft for the rotor.

According to another feature of the invention the connecting bolt is tubular and provided at one end with an abutment for fixing its axial position with relation to one end section of the rotor and provided with means at its other end for engagement with the other end section of the rotor or a member connected therewith, in order thereby to permit a jamming of the sections in the axial direction.

The use of a tubular bolt for jamming the sections together reduces the total weight of the rotor, while at the same time allowing a central, preferably also tubular, bolt to extend through the first mentioned tubular bolt for connecting the rotor to the rotor of another axially spaced machine, as for instance, for connecting the rotor of a compressor to the rotor of a turbine for driving the compressor.

According to a further feature of the invention the said last-mentioned means comprises a threaded portion of the bolt, allowing a jamming of the discs by turning the bolt.

According to still another feature of the invention the abutting flanges of the discs are located on a small radius as compared with the outer radius of the discs, other axial flanges being provided at or near the outer periphery of the discs which are adapted after the sections are jammed together to be rigidly connected together, as by welding.

The above mentioned and other features of the invention will more clearly appear from the following description with reference to the accompanying drawing which shows a substantially diagrammatic axial section of one half-part of a machine having a rotor according to the invention and which is hereinafter referred to as a compressor.

2

In the drawing the numeral 1 indicates the casing of the machine, 2 is the intake for the fluid (as air) to be compressed, and 3 is a transition passage leading to a combustion chamber indicated in the drawing by portions of its casing shown to the right of the passage 3. Secured to the inside of the casing 1 are guide blades 4. The moving blades 5 of the compressor which are arranged alternately with the guide blades are carried by a rotor comprising a plurality of axial sections, preferably, as shown, so that each section carries an annular set of moving blades.

Each section of the rotor consists of a thin disc 6 provided between its inner and outer peripheries with a flange 7 on one side or both sides and having further, near its outer periphery, at a distance from the respective set of blades, another flange or flanges 8. The flanges 7 and 8 are, preferably, cylindrical so that in the assembled state of the rotor they may act as two concentric cylinders.

Extending through the hub portions of the discs 6 is a tubular bolt 9. Said bolt carries at its one end (that is to say, the right hand one in the drawing) an external collar 10 and is formed with a threaded portion 11 at its other end. Bearing against said collar 10 is an internal collar 12 provided near the outer end of a conical sleeve 13 widened towards its inner end where it bears against a flange 7 of the adjacent end section of the rotor. The opposite threaded end of the tubular shaft 9 is screwed (at 11) into a threaded boring of a conical sleeve 14 rigidly connected at its outer end to a shaft 15 for transmitting the starting torque to the rotor and bearing at its inner, wider end against a flange 7 of the respective end section of the rotor.

By tightening the tubular bolt 9 the rotor sections may be jammed between the members 13 and 14 with such a power as to cause the flanges 7 to tightly abut against each other and behave like a tubular shaft rigidly connected to the tubular bolt 9 through the intermedium of the end members 13 and 14. In order to improve the connection between the rotor sections the flanges 8 may be welded together, as indicated at 16. To allow turning of the tubular bolt 9 by means of a key the bolt is provided with a head 17 outside the collar 10.

The end members 13, 14 of the composite tubular shaft represented by the flanges 7 are rotatably mounted in the stationary frame of the machine by means of ball bearings 18 and 19, respectively, so that they may act as journals for said shaft and thus for the rotor.

Owing to the small wall thickness and the great length of the tubular bolt 9 it is impossible merely by mechanical means, that is to say, mere-

ly by screwing the bolt into the member 14, to effect a sufficiently strong jamming together of the rotor sections.

According to the invention this jamming operation is effected by first tightening the tubular bolt 9 as far as possible by turning it by means of a key, then heating the bolt until a predetermined extension thereof is obtained and, finally, again tightening the bolt as far as possible. The heating can be effected by means of a hot fluid, as hot air, oil or steam, which is passed through the bolt, or by electric heating, as for instance, according to the dip heating method. The extension obtained by heating the bolt may be measured by means of a suitable gauge 20. After the second tightening operation the tubular bolt is allowed to cool and contract. The tensile strain may be measured and controlled by a suitable tension meter 21, constructed, for instance, according to the so called strain-gage-method, that is to say, with the use of a pasted electric resistance wire.

In order to connect the described rotor to the rotor of an adjacent coaxial machine, as for coupling together the rotor of a compressor and the rotor of a turbine for driving the compressor a, preferably, tubular bolt 22 extending through the tubular bolt 9 may be used. To this end said bolt 22 is fixed axially at its one end with relation to the bolt 9 by means of an external collar 23 of the bolt 22 bearing against an internal collar 24 of shaft 15, while the other end of the bolt 22 is screwed into an internally threaded flange 25 of a connecting member 26 provided between the rotor of the compressor and the turbine rotor which may be bolted to the turbine rotor, as indicated. Tightening of said bolt 22 may be effected in the way already described in connection with the description of the tubular bolt 9.

Inserted between the rotor of the compressor and the transition element 3 is a device, indicated as a whole at 27, for balancing the axial thrusts.

In order that the collars 10 and 23 of the bolts 9 and 22, respectively, may not be in the way of each other, they are located at opposite ends of the compressor rotor.

What I claim is:

A multi-section rotor for elastic fluid machines of the axial flow type, comprising in combination, a set of axially spaced discs for constituting the sections of the rotor, concentric axial flanges located at a small diameter on said discs for abutting against each other in the assembled rotor so as to form a composite tubular shaft therefor, other concentric axial flanges provided at a greater diameter of the discs for effecting a rigid connection between adjacent discs, sleeve-shaped conical end portions connected at their wider ends to opposite ends of the tubular shaft formed by the said first-mentioned flanges, said conical portions being shaped at their smaller ends as journals a tubular bolt extending centrally through said tubular shaft and associated journals, abutments on one end of said bolt for engaging with one of said journals and a screw-thread at the other end of said bolt for engaging with the other journal for allowing jamming of the set of discs by turning the bolt, another bolt extending centrally through said first-mentioned bolt, abutments on one end of said other bolt for engaging with one of said journals, a connecting member having a screw-threaded portion, the other end of said other bolt having a screw-threaded portion for engaging said connecting member, and the said abutments of the bolts being provided at opposite ends of the rotor structure in order to prevent interference with one another.

FRANS ERIC OSSIAN ÖSTMAR.
